(57) **CLAIM**

We claim, the ornamental design for a fender step for trailer, as shown and described.

DESCRIPTION

FIG. 1 is a perspective view of the fender step for trailer showing our new design;

FIG. 2 is a second perspective view thereof;

FIG. 3 is a top plan view thereof;

FIG. 4 is a bottom plan view thereof;

FIG. 5 is a left side view thereof;

FIG. 6 is a right side view thereof;

FIG. 7 is an end view thereof; and,

FIG. 8 is an end view thereof.

In FIG. 2, the broken line showing of an end cap depicts environmental subject matter and forms no part of the claim.
